DENTAL INLAY CLAMP

Jerome I. Moray, West Orange, N.J.

Application March 26, 1951, Serial No. 217,585

4 Claims. (Cl. 32—63)

1

The invention relates to a dental instrument, and more particularly to means facilitating the procedure of cementing an inlay within a tooth.

It has been the practice to insert an inlay within a tooth cavity, lined with cement, and for the dentist to apply digital pressure upon the inlay until the cement has set. With certain types of inlays, such as within occlusal or incisal surfaces, the patient may apply pressure upon the inlay by a biting action. Whether pressure is digitally applied by the dentist or by the biting action of the patient, it is most difficult to apply the continued amount of pressure for the comparatively long period of time required, usually about ten (10) minutes. While the inlay cement is setting, it generates expansion forces, probably due to the heat of expansion of the composition, which forces must be overcome. Moreover, whether the pressure upon the inlay is being applied by the dentist or the patient, the physical effort required is tiring, and submits the individual to undue strain. Also, when the dentist is so occupied, he is unable to gainfully pursue other activities which may be necessary.

In accordance with the present invention, an instrument is provided to apply firm, constant and continuous pressure upon the inlay for the length of time required for the cement to set. By means of the instrument of my invention, which takes the form of a clamp, possible displacement of the inlay because of the human element is obviated. The physical strain upon either the dentist or the patient is eliminated.

My dental inlay clamp is applicable to most inlays on posterior teeth, to labial and lingual inlays on anterior teeth, and any anterior inlays that have an incisal drop.

The device is simple in construction, easy to operate, and permits the dentist to perform other services while the inlay is being properly pressed and secured in place.

To the accomplishment of the foregoing objects and such other objects as hereinafter may appear, my invention relates to a dental inlay clamp as described in the following specification, together with the accompanying drawing, in which:

Fig. 1 is a front elevation of the dental inlay clamp;

Fig. 2 is a vertical section taken approximately in the plane of the line 2—2 of Fig. 1;

Fig. 3 is a bottom view of the clamp shown in Fig. 1;

Fig. 4 is a top view of the clamp shown in Fig. 1;

2

Fig. 5 is an enlarged, partial view of the means for applying pressure to an inlay in an occlusal or incisal surface;

Fig. 6 is an enlarged view of one of the tooth or inlay clamping members of the clamp; and

Fig. 7 is a view illustrating the manner in which the clamp is used with various types of inlays.

Referring to the drawings, particularly Fig. 1, the inlay clamp comprises a base member or support 10 provided with a pair of spaced arms 12 and 14, each arm depending from the support. The arms 12 and 14 may be substantially parallel to each other, and each is disposed substantially at a right angle to the support 10. In the preferred embodiment of the invention, the support and arms are integrally formed from a single piece of metal, as shown.

A pair of tooth or inlay clamping members 16 and 18 are provided on arms 12 and 14, respectively, at or near the ends thereof. The clamping members 16 and 18 are oppositely disposed with respect to each other, and each lies in a plane substantially perpendicular to its arm. Preferably, one clamping member is formed integrally with its arm, while the other is mounted on its arm for movement toward or away from the first mentioned clamping member. As shown, the clamping member 16 is formed by bending the end of the arm 12 substantially at a right angle thereto. The lower end of arm 14 is tapped and internally threaded at 20 to receive a screw 22, the head of which is knurled at 24 to facilitate turning thereof. The clamping member 18 is mounted on the end of the screw 22. As shown in Figs. 3, 4 and 6, the clamping members 16 and 18 have their working faces formed in the shape of a shallow V to conform substantially to the contour of the surfaces of the teeth which they will engage.

In order that the clamping members will always be in proper position for engagement with the tooth proper, or an inlay to which it is desired to apply pressure, one of the clamping members, in this instance, member 18, is mounted to rotate freely on the end of the screw 22, as shown in Fig. 6. The end of the screw 22 is provided with a ball portion 21 received within a socket 23 formed in the jaw, the edges of the socket being bent over to make the connection. The construction of the clamp thus far described will serve to apply pressure to inlays within bucco-gingival, labio-gingival and lingual surfaces.

For the added function of applying the desired firm and continuous pressure to an inlay on an occlusal surface, the clamp is provided with added

means for applying pressure in a direction substantially perpendicular to the direction of pressure application applied by the clamping members 16 and 18. To carry this added inlay pressure-applying means, the support 10 is provided with a slot 26 therethrough extending longitudinally and substantially centrally of the support. As more particularly shown in Fig. 2, a slide 28 is mounted on the support 10 for movement along its length. The slide 28 is formed by bending the ends of a strip of metal around the support 10. The ends of the slide are spaced from each other to provide a central, longitudinally extending slot 30. A vertical pressure-applying member 32 in the form of a screw passes through the slide slot 30, the support slot 26, and through an internally threaded aperture 34 in the otherwise solid side of the slide 28. The head of the screw 32 is provided with a knurled portion 36. The lower end of the screw 32 is provided with a cap 38 which, as shown in Fig. 5, is mounted to rotate freely. The end of the screw is provided with a ball portion 39 over which the peripheral edge of the cap is drawn. The end of the pressure member 32 is formed with the freely rotatable cap 38 to prevent the application of a twisting force or torque to the inlay.

Referring to Fig. 7, it will be observed that the described clamp is useful for most types of inlays. To secure an inlay 40 within the lingual surface of a tooth 41, the clamping member 16 is placed in contact with the inlay. The member 18 is moved into pressure contact with the tooth proper by turning the knurled head of the screw 22 until the inlay and the opposite side of the tooth are firmly gripped between the clamping members. The swivable or rotatable mounting of the member 18 permits its working face to best engage the substantially convex tooth surface.

As also shown in Fig. 7, when it is desired to secure an inlay 42 within a bucco-gingival or labio-gingival surface, the same described adjustment of the clamp is followed. The clamping member 18 in this instance bears against the inlay instead of the tooth proper. The described rotatable mounting of the member 18 upon the end of the screw 22 serves to apply the desired pressure to the inlay without exerting a twisting force thereon.

As also shown in Fig. 7, when it is desired to apply pressure to an inlay 44 in an occlusal or incisal surface, the clamp is secured to the tooth proper by simply turning the knurled head 24 of the screw 22 until both sides of the tooth proper are firmly gripped as a support by the members 16 and 18. The slide 28 is moved along the support 10 until the pressure-applying member 32 is located directly above the inlay. The member 32 is then turned by means of the knurled head 36 until the cap 38 is brought into pressure engagement with the inlay. The cap 38 being mounted in the manner described, pressure is applied to the inlay in a direction normal to the inlay, without twist or torque tending to dislodge the inlay.

The construction of the dental inlay clamp of the present invention and the operation thereof, as well as the many advantages resulting therefrom will, in the main, be fully apparent. Most types of inlays can be maintained in the cavity preparation under firm, continuous and properly applied pressure, while allowing the dentist to perform other services while the cement is setting. The clamp is applicable to most inlays on posterior teeth, to labio-lingual inlays on anterior

teeth, or anterior inlays that have an incisal drop. By exerting firm, constant, and normally applied pressure on the inlay, the instrument acts to eliminate any displacement of the inlay due to expansion resulting from imperfect application of pressure by the dentist or the bite of the patient, and as occasioned by the expansion forces exerted by the setting cement.

While I have shown a preferred form of the instrument, it will be appreciated that changes may be made in the construction thereof without departing from the spirit of the invention as defined in the following claims.

I claim:

1. A dental inlay clamp comprising a support, a pair of spaced arms each depending from said support, a tooth or inlay clamping member having a working face conforming substantially to the contour of a tooth provided on each of said arms and spaced from said support, said members each being substantially perpendicular to its arm and oppositely disposed with respect to each other, means for imparting movement to at least one of said tooth or inlay clamping members, a slot provided in said support, a slide mounted on said support and movable across the slot, and a screw member having a pressure surface smaller than an entire occlusal surface threaded through said slide and passing through said slot for applying pressure in a direction perpendicular to the support upon an inlay in an occlusal surface.

2. A dental inlay clamp comprising a support, a pair of spaced, substantially parallel arms each depending from said support and integrally formed therewith, a tooth or inlay clamping member having a working face conforming substantially to the contour of a tooth provided at the end of one of said arms, said member being substantially perpendicular to the arm and integrally formed therewith, a second tooth or inlay clamping member also having a working face conforming substantially to the contour of a tooth carried near the end of the second arm and substantially perpendicular thereto, said members being oppositely disposed with respect to each other, means for imparting movement to said second member, a slot provided in said support, a slide mounted on said support and movable across the slot, and a screw member having a pressure surface smaller than an entire occlusal surface threaded through said slide and passing through said slot for applying pressure in a direction perpendicular to the support upon an inlay in an occlusal surface.

3. A dental inlay clamp comprising a support, a pair of spaced, substantially parallel arms each depending from said support and integrally formed therewith, a tooth or inlay clamping member having a working face conforming substantially to the contour of a tooth provided at the end of one of said arms, said member being substantially perpendicular to the arm and integrally formed therewith, a second tooth or inlay clamping member also having a working face conforming substantially to the contour of a tooth mounted on the end of a screw threaded through the second arm and substantially perpendicular to the arm, said tooth or inlay clamping members being oppositely disposed with respect to each other, said second member being rotatably mounted to permit adjustment of its working face to the contour of a tooth, a slot provided in said support, a slide mounted on said support and movable along the slot, and a screw member having a pressure surface smaller than an entire

occlusal surface threaded through said slide and passing through said slot for applying pressure in a direction perpendicular to the support upon an inlay in an occlusal surface.

4. A dental inlay clamp comprising a support, a pair of spaced, substantially parallel arms each depending from said support and integrally formed therewith, a tooth or inlay clamping member having a working face conforming substantially to the contour of a tooth provided at 10 the end of one of said arms, said member being substantially perpendicular to the arm and integrally formed therewith, a second tooth or inlay clamping member also having a working face conforming substantially to the contour of 15 a tooth mounted on the end of a screw threaded through the second arm and substantially perpendicular to the arm, said tooth or inlay clamping members being oppositely disposed with respect to each other, said second member being 20 rotatably mounted to permit adjustment of its working face to the contour of a tooth, a slot

provided in said support, a slide mounted on said support and movable across the slot, and a screw member threaded through said slide and passing through said slot, said screw member being provided with a rotatable cap at the end thereof for applying pressure in a direction perpendicular to the support upon an inlay in an occlusal surface, said cap having a pressure-applying surface smaller than the entire occlusal surface.
